UNITED STATES PATENT OFFICE

OTTO GEISLER AND GEORGE W. SETH, OF CHICAGO, ILLINOIS

EXPANSION DEVICE FOR DIAGONALS AND BULKHEAD WIRES

Application filed May 27, 1929. Serial No. 366,457.

Our invention relates to improvements in expansion devices for diagonals and bulkhead wires, and it consists in the combinations, constructions, and arrangements herein described and claimed.

An object of our invention is to provide means for adjusting bulkhead wires and bracing such as that disclosed in our prior patent No. 1,715,829, in which Otto Geisler is the inventor and George Seth is an assignee of a part interest.

A further object of our invention is to provide means whereby the internal bracing structure within an airship may be accurately 15 and quickly adjusted to conform to the contraction and expansion of the casing of the ship and certain of its associated bracing structure.

A further object is to provide means whereby certain of the bulkhead wires in an airship 20 may be given a certain amount of slack for supporting a gas cell upon one side of the bulkhead wires in the event that a gas cell upon the opposite side should become deflated.

A further object is to provide a device of 25 the type described whereby a plurality of bracing members and a plurality of bulkhead wires may be easily placed under the proper tension with a minimum of effort.

A further object is to provide means whereby a plurality of bracing members and bulkhead wires in an airship may be adjusted simultaneously and the same amount.

Other objects and advantages will appear 35 in the following specification, and the novel features of the invention will be particularly pointed out in the appended claims.

Our invention is illustrated in the accompanying drawings, forming part of this application, in which

Figure 1 is a longitudinal sectional view of a portion of our invention,

Figure 2 is a sectional detail view taken along the line 2—2 of Figure 1,

Figure 3 is an enlarged detail view taken along the line 3—3 of Figure 1,

Figure 4 is a diagrammatic view of an airship embodying our invention,

Figure 5 is an enlarged diagrammatic longitudinal sectional view of a portion of an

airship showing our invention as applied thereto,

Figure 6 is an enlarged detail view of a portion of the bracing structure of the airship, and

Figure 7 is a diagrammatic detail view of a portion of the structure of the ship.

In carrying out our invention, we make use of an airship 1 such as that shown in Figure 4. The ship comprises an outer casing 2, see Figures 5 and 7. The casing is preferably formed from suitable sheet metal. The casing is disposed upon longitudinal supporting members 3. Transverse members 4 are disposed between the longitudinal members 3 for holding the latter in spaced relation, see Figure 7.

In referring to Figure 5, it will be seen that we have provided inner longitudinal members 5 which are spaced from the members 3. The members 5 are held in spaced relation with respect to the members 3 by means of suitable supporting members 6. The members 5 are held in spaced relation by means of inner transverse members 7. It will be seen in referring to Figure 7 that the transverse members 4 and 7 and their associate bracing form a plurality of supporting rings at points 8 indicated in Figure 5 and also diagrammatically at 8 in Figure 4.

In Figure 5 we have shown rigid diagonal bracing 9 for supporting the longitudinal members 5 and also the longitudinal members 3. Fixed diagonal members 10 are also provided for supporting the longitudinal members as shown in Figure 7. In Figures 4 and 5 we have shown the ship as being provided with a centrally disposed longitudinal shaft 11. In Figure 1 we have shown a detail view of the shaft. The shaft 11 comprises a series of portions 12, the ends of which are connected together by means of the supporting structure for an expansion device, such as that shown in Figure 1. The expansion devices are disposed in a plane in alignment with the supporting rings 8, see Figure 5.

In Figure 1 we have shown a plurality of bars 13 riveted to the ends of the pipes 12 as at 14. The opposite ends of the bars 13 are

connected with a coupling device 15 by means of bolts or screws 16. A pulley 17 is supported by the coupling members 15. It will be seen that the pulley 17 comprises pieces 18 and 19. The parts may be secured together by means of bolts 20 and 21. The pulley 17 is provided with a hub portion 22 having flanges 23 which are disposed within grooves 24 in the coupling members 15. The pulley 17 is disposed in alignment with rings 8. In Figure 1 we have shown the bars 13 upon only one side of the pulley 17. The bars, however, are provided upon both sides of the pulley, but, in view of the fact that the construction is identical upon each side, the showing and description of the structure upon one side will of course suffice.

A screw member 25 is secured to the hub portion 22 of the pulley 17. The screw member extends laterally from each side of the pulley and is disposed within the bars 13. The screw member is provided with right-hand threads 26 and left-hand threads 27. A disc member 28 is provided with threads 25 whereby the member may be disposed upon the left-hand threads 27. A second disc 29 is provided with threads and is disposed upon the threads 26. The disc 29 is provided with a plurality of prongs 30 having openings 31 for receiving the ends of bulkhead wires 32. The opposite ends of the bulkhead wires are secured to the supporting rings 8 at 33, see Figures 5 and 6. In referring to Figures 1 and 3, it will be seen that the bulkhead wires 32 cross as at 34 and are alternately disposed about a ring 35.

In Figure 5 we have shown diagonal bracing members 36 hingedly secured at 37 upon the rings 8, as shown in detail in Figure 6. The diagonal bracings 36 are provided with a hinge at 38. The opposite ends of the diagonals are connected with turn-buckles 39, see Figures 5 and 1. The turnbuckles are in turn connected with the disc member 28 through the medium of threaded rods 40. The diagonals are provided with suitable cables 41 whereby the diagonals may be moved into the collapsed position shown at 42 in Figure 5.

A gas-containing cell 43 is disposed between alternate rings 8, see Figure 5. The operation of the diagonal members 36 and of the cells 43 has been clearly set forth in the patent application above referred to. The couplings 15 comprise members 44 and 45, see Figure 3. The members are rigidly secured together by means of bolts 46. The hub 22 of the pulley 17 is keyed to the screw member 25 by means of keys 47.

In Figure 3 we have shown a beaded chain 48 as disposed upon the pulley 17. The chain 48 passes around the pulley and to a position within an operating compartment in the body of the ship. The chain may be connected with suitable automatic mechani-

cal devices for turning the pulley or the pulley may be turned manually through the medium of the chain 48.

From the foregoing description of the various parts of the device, the operation thereof may be readily understood. It is important in airship constructions to provide means whereby the internal bracing may be accurately adjusted to conform to the variations in expansion and contraction of the body portion of the ship. In referring to Figure 1, it will be seen that when the pulley 17 is rotated, the screw member 25 will be rotated. Rotation of this member will of course move the members 28 and 29 toward or away from each other, depending upon the direction of rotation of the pulley 17. When the pulley 17 is rotated for moving the members 28 and 29 toward each other, the diagonals 36 and the bulkhead wires 32 will of course be placed under increased tension. When, however, the members 28 and 29 move in opposite directions, the tension in the diagonals 36 and the bulkhead wires 32 will be decreased to the amount that the members 28 and 29 are moved. The ring 28 is provided with no other supporting structure than the bulkhead wires 32. It will be seen that when the bulkhead wires 32 are placed under tension, the ring 35 will of course automatically be centered.

In view of the fact that the operation of each unit is identical, the description is being confined to a single unit. In referring to Figure 5, we have shown a unit A operatively connected with diagonals 36 and bulkhead wires 32. At B we have shown a unit adapted to operate bulkhead wires alone. The unit B is identical with the unit A with the exception that the threads 27 and the ring 28 are omitted. The bulkhead wires 32 support the central shaft 11.

With our invention it is possible to provide a certain amount of slack in the bulkhead wires for supporting a gas cell when the companion cell should for any reason become deflated. In other words, by providing a certain amount of slack in the bulkhead wires, the latter will of course support a greater pressure than when the bulkhead wires are drawn taut. When the diagonals are collapsed, they may be disconnected from the members 28.

We claim:

1. In an airship of the lighter than air type, supporting members disposed in spaced relation, a central supporting member, adjusting means disposed upon said central supporting member, bracing members connected with certain of said supporting members and said adjusting means, and bulkhead wires connected with said supporting members and the adjusting means whereby the bulkhead wires and the bracing members may be placed under various degrees of tension.

2. In an airship of the lighter than air type, a plurality of movable bracing members, a plurality of bulkhead wires, and means operatively connected with said plurality of bracing members and the plurality of bulkhead wires whereby the same may be placed and held under various degrees of tension. 70
3. In an airship of the lighter than air type, a plurality of bracing members, a plurality of bulkhead wires, and means for placing said plurality of bracing members and said plurality of bulkhead wires simultaneously under tension, said last-named means being adapted to place said bracing members and the bulkhead wires under various degrees of tension. 76
4. In an airship construction, a plurality of bulkhead wires, screw means for placing said bulkhead wires under various degrees of tension, a plurality of bracing members, and screw means for placing said plurality of bracing members under various degrees of tension, said screw means being operable simultaneously. 85
5. In an airship construction, a supporting framework, a central supporting member, a pair of screw-actuated elements associated with said central supporting member, and a plurality of bracing elements connected with each of said screw elements, said screw elements being movable simultaneously in opposite directions for placing the bracing elements under tension. 95
6. In an airship construction, a supporting framework, a plurality of bulkhead wires connected with the framework, and a plurality of screw means operatively connected with the bulkhead wires and movable as a unit for placing the same under tension. 105
7. In a device of the type described, an actuating wheel provided with a screw element upon each of its sides and aligned with its axis of rotation, and a plurality of tensional elements mounted upon each of the screw elements, said screw elements being formed whereby the units comprising the plurality of tensional elements upon each side of the wheel may be moved toward or away from each other when the actuating wheel is turned. 110
8. In an airship construction, a plurality of bulkhead wires radially arranged with respect to the airship, a centering ring, said bulkhead wires being alternately passed upon opposite sides of the centering ring, and a movable member having elements associated therewith and movable toward or away from each other when the former is moved, the inner ends of the bulkhead wires being alternately connected with said elements. 120
9. In an airship construction, a plurality of bulkhead wires radially arranged with respect to the airship, a centering ring, said bulkhead wires being alternately passed upon opposite sides of the centering ring, a movable member having elements associated therewith and movable toward or away from each other when the former is moved, the inner ends of the bulkhead wires being alternately connected with said elements. 125
10. In an airship construction, a plurality of bulkhead wires radially arranged with respect to the airship, a centering ring, said bulkhead wires being alternately passed upon opposite sides of the centering ring, a movable member having elements associated therewith and movable toward or away from each other when the former is moved, the inner ends of the bulkhead wires being alternately connected with said elements, a plurality of bracing members, and elements associated with said movable member and movable toward and away from each other when the latter is moved, said last-named elements being operatively connected with said bracing members. 89
- Signed at Chicago, in the county of Cook, and State of Illinois this 24th day of May, A. D. 1929.
